UNITED STATES PATENT OFFICE.

FRANK W. MILLER, OF WOOSTER, OHIO.

DOOR-HANGER.

SPECIFICATION forming part of Letters Patent No. 793,386, dated June 27, 1905.

Application filed June 23, 1903. Serial No. 162,740.

To all whom it may concern:

Be it known that I, FRANK W. MILLER, a citizen of the United States, residing at Wooster, in the county of Wayne and State of Ohio, have invented new and useful Improvements 5 in Door-Hangers, of which the following is a specification.

My invention relates to improvements in barn-door hangers; and it consists in the particular construction and combination of devices hereinafter described and claimed.

One object of my invention is to effect improvements in the construction of the link which forms the pivotal or hinged connection 15 between the door-strap and the supporting-wheel housing.

A further object of my invention is to effect improvements in the construction of the door-strap.

20 A further object of my invention is to combine with the hook-piece of the wheel-housing a link having a hinge-bar engaged by the said hook-piece and a door-strap having intermediate portions which are recessed on the upper 25 side of the base-bar of the link and bear under the hook-piece to retain the latter against casual disengagement from the link-bar and to also retain the door-strap in place on the link.

In the accompanying drawings, Figure 1 is 30 a perspective view of a barn-door hanger embodying my improvements. Fig. 2 is a horizontal sectional view taken on the plane indicated by the line *a a* of Fig. 1. Fig. 3 is a vertical section view of the same, taken on the 35 plane indicated by the line *b b* of Fig. 1. Fig. 4 is a similar view taken on the plane indicated by the line *c c* of Fig. 1. Fig. 5 is a detail perspective view of the link.

In the embodiment of my invention I 40 provide a link 1, which comprises a base-bar 2, flat on its lower side to bear on the upper edge of the door, end pieces 3, and a hinge-bar 4, which connects the said end pieces and is disposed above the base-bar 1. Said end pieces 45 form shoulders 5 at the ends of the hinge-bar and are undercut on their inner sides to form recesses 6, the base-bar being recessed transversely on its upper side, as at 7, said recesses 7 communicating with and merging in the recesses 6. The sides of the central portion of

the base-bar are recessed, as at 8, and on the upper side of the base-bar is a longitudinally-disposed rib 9, which extends between the recesses 7.

The door-strap 10 is U-shaped. Its central 55 or connecting portion 11 is adapted to bear against one side of a door, and the arms of the strap are bent at right angles to form the horizontally and transversely disposed portions 12, which engage and fit in the recesses 60 67 of the end pieces and base-bar of the link, the extremities of the arms being turned downwardly, as at 13, to bear against the side of the door opposite the central portion 11.

The housing 14, in which is mounted the 65 supporting wheel or roller 15, that operates on the track-rail, (not shown,) is provided at its lower side with a hook portion 16, which engages the hinge-bar 5, and thereby a pivotal or hinge connection is effected between the 70 wheel-housing and the link. The under side of the hook portion 16 of the wheel-housing bears on the upper sides of the cross portions 12 of the door-strap, and thereby the said hook portion of the wheel-housing is prevented 75 from becoming casually disengaged from the hinge-bar of the link.

From the foregoing description, taken in connection with the accompanying drawings, the construction and operation of the invention 80 will be readily understood without requiring a more extended explanation.

Various changes in the form, proportion, and the minor details of construction may be resorted to without departing from the principle or sacrificing any of the advantages of 85 this invention.

Having thus fully described my invention, what I claim as new, and desire to secure by Letters Patent, is—

1. In a door-hanger, a link for the purpose set forth, comprising a base-bar, end pieces, and a hinge-bar connecting the end pieces and above the base-bar, the latter having transverse notches 7 on its upper side, and the end 95 pieces being undercut on their inner sides to form notches 6 which communicate with said notches 7, substantially as described.

2. In a barn-door hanger, the combination of a link comprising a base-bar, end pieces, 100

2
and a hinge-bar, and provided with transverse notches; a door-strap having cross portions in said notches, and a wheel-housing having a hook portion pivotally engaging the hinge-bar and bearing on the cross portions of the door-strap, substantially as described.

5 In testimony whereof I have hereunto set

my hand in the presence of two subscribing witnesses.

FRANK W. MILLER.
